UNITED STATES PATENT OFFICE

169,348

LAVATORY

Willard G. Young, Robinson, Ill., assignor to
W. A. Case and Son Manufacturing Company,
Buffalo, N. Y., a corporation of New York

Application November 8, 1952, Serial No. 22,194

Term of patent 14 years

(Cl. D4—2)

To all whom it may concern:

Be it known that I, Willard G. Young, a citizen of the United States of America and residing at Robinson, in the county of Crawford and State of Illinois, have invented a new, original, and ornamental Design for a Lavatory, of which the following is a specification, reference being had to the accompanying drawings, forming part thereof.

Fig. 1 is a perspective view of a lavatory embodying my new design, this view being taken from the front to the left of the lavatory.

Fig. 2 is a top plan view thereof.

Fig. 3 is a side elevational view thereof, viewed from the right of the lavatory as shown in Fig. 2, the left hand side being similar in appearance.

Fig. 4 is an elevational view of the front thereof.

Fig. 5 is an elevational view of the rear thereof.

I claim:

The ornamental design for a lavatory, substantially as shown.

WILLARD G. YOUNG.
